(57) **CLAIM**

The ornamental design for an alignment aid for golf club, as shown and described.

DESCRIPTION

FIG. 1 is a front perspective view of a golf club including an alignment aid. The alignment aid includes a plurality of markings on a hosel of the golf club. The markings are able to be used by a golfer to achieve various alignments corresponding to various types of golf shots, such as pitch shots, bunker shots, and chip shots.

FIG. 2 is a front view of a portion of the golf club including the alignment aid.

FIG. 3 is a rear view of a portion of the golf club including the alignment aid.

FIG. 4 is an end, or face-on, view of a portion of the golf club including the alignment aid; and,

FIG. 5 is a top view of a portion of the golf club including the alignment aid.

The dot dash lines shown in the drawings form no part of the claimed design.
